UNITED STATES PATENT OFFICE.

THEODOR BÜDINGEN, OF CONSTANCE, GERMANY.

MOVEMENT-CURE APPARATUS.

964,898.

Specification of Letters Patent. Patented July 19, 1910.

Application filed March 17, 1910. Serial No. 549,903.

To all whom it may concern:

Be it known that I, THEODOR BÜDINGEN, a subject of the Grand Duke of Baden, and residing at 2 Glärnischstrasse, Constance, Germany, have invented certain new and useful Improvements in Movement-Cure Apparatus; and I do hereby declare the following to be a full, clear, and exact description of the invention.

10 The movement cure-apparatus forming the subject-matter of my invention is for imparting the beneficial action of walking and ascending to the circulation of the blood of clinics, particularly those whose circulation requires promoting, as *e. g.* those suffering from heart disease. To this end, by means of suitable gearing two pendulum arms are oscillated which are so arranged that the suitably attached legs of a patient 20 located in a position of rest can be moved. Owing to the motion which is caused hereby, in consequence of the legs being lifted there is obtained, besides a pumping action, a pressure action which is to be attributed to 25 hydrostatic laws and which likewise promotes the circulation of the blood.

One illustrative embodiment of my invention is represented by way of example in the accompanying drawing, wherein:—

30 Figure 1 is a side elevation, Fig. 2 a front elevation, and Fig. 3 a top plan view on an enlarged scale showing part of my apparatus; Figs. 4 to 8 show details likewise on an enlarged scale.

35 Referring to the drawings, the entire gearing is mounted on a frame comprising a base plate 1 and stays or uprights 2, 3, 4 and 5 which approach one another at the top.

40 On the base plate 1 is secured by means of screws or bolts 7, 8, 9, 10 a bearing 6 in which is journaled a shaft 11 secured on which are two cam-wheels 12 and 13, of the form clearly shown in Fig. 4, having grooves 45 14 and 15 in the faces thereof facing one another. Projections 16 and 17, in which pivots 18 and 19 are secured, are cast on the base of the bearing 6. Fulcrumed on these pivots are two levers 20 and 21 carrying short pivots 22 and 23 (Fig. 4), on which are journaled rollers 24 and 25 which can run in the grooves 14 and 15, respectively, of the cams 12 and 13, respectively. These 50 cams or their grooves comprise a circular and an elliptical portion and are displaced 180° relatively one to the other. With the

ends of the levers 20 and 21 connecting rods 26 and 27 are pivotally connected, whose top ends are pivotally connected with the arms 28 and 29 of two angle levers mounted to 60 rock on a shaft 38 secured in the frame.

In order to be able to vary the point of application of the connecting-rods 26 and 27 at the arms 28 and 29 of the angle levers, the arms are forked and screws 30 and 31 65 are journaled in the forked portions (Fig. 8) and can be rotated by hand-wheels 32 and 33. On the screws are nuts 34 and 35 having lugs 36 (Fig. 8), to which the connecting-rods are pivoted. The other arms 70 39 and 40 of the angle levers are pivotally connected with additional connecting-rods 41 and 42 which are pivoted to pendulum arms 43 and 44 which oscillate on a shaft 45. This shaft is journaled in a support or 75 bracket 46 which is formed as a slide (Figs. 5 and 6) and can be moved upward and downward on the frame. To this end, a shaft 47 is journaled in the slide and carries at one end a hand-wheel 48 and at the other 80 end a pinion 49 meshing with a rack 50 secured on the frame. By turning the hand-wheel 48 the pinion 49 is caused to roll on the rack 50 and the slide is moved. In order to secure it in position for the time being, a 85 locking device *e. g.* a clamping screw 51, is provided (Fig. 5) which carries a handle 52 and can be pressed against the face 53 of the slide 46 by turning the handle. At the bottom ends of the pendulum arms 43 and 44 90 are provided pivoted attachment-devices for the legs. These comprise shoes 73 adapted to the shape of the foot and having pivoted thereto rods 78 to which bandages 79 and 80 are secured.

95 Loose on the shaft 11 and in immediate proximity to the cam-wheel 12 is a worm-wheel 37 meshing with a worm thereunder which is journaled in bearings 55 and 56 and driven by an electric motor 57. Adjacent to the worm-wheel 53 is a clutch 58 which is movable axially on the shaft 11 but prevented from rotating relatively to the shaft. On the outside end of the shaft 11 is a loose sprocket wheel 59, to which a rotatory motion can be imparted by means of a chain 62 from a sprocket wheel 61 which is journaled in the frame and carries a handle 60. When the clutch is moved in the one or other direction its teeth 63 coact 105 with the teeth 64 of the worm wheel 53 or with the teeth 65 of the sprocket wheel 59.

In order to be able to secure the apparatus to a bed or the like, attached to the base plate 1 is a frame 66 in which two shafts 67 and 68 are journaled. These shafts are 5 provided at their ends projecting beyond the frame 66 with handles 87 and 88, by which they can be turned. Secured on the shaft 67 are jaws 69, on whose outer ends are mounted pieces 70 (Fig. 7) of soft material, as india-rubber or leather, while their bottom ends each carry a catch or detent 71, against which locking levers 75 secured on the shaft 68 can lie. Screws 74 which can be moved by hand-wheels 72 and are 10 mounted in the uprights 3 and 5 serve as abutments, the front ends of these screws being likewise provided with protective members 76 similar to the members 70.

The frame is provided with rollers 77 for 20 more readily moving it. In order to fix the apparatus firmly on the ground after it has been attached at the place of rest of the patient, two screws 83, which can be moved by hand-wheels 82, are mounted in the base- 25 plate and provided at their bottom ends with protective members 86. By turning the hand-wheels 82 the rollers 77 located near them are raised from the ground.

My apparatus is manipulated and operates 30 as follows:—After the elevation and the amplitude of the pendulum arms 43 and 44 have been adjusted suitably for the patient by turning the hand-wheel 48 on the one hand, and the hand-wheels 32 and 33 on the 35 other hand, presupposing that the apparatus is to be driven by the motor 57 the clutch 58 is caused to engage with the worm wheel 37, whereupon the motor is started. This rotates the worm which drives the worm 40 wheel 37 coacting with the clutch 58, which, again, imparts its motion to the shaft 11 so that the cams 12 and 13 are rotated. In consequence of the shape of the grooves 14 and 15 of the cams 12 and 13 which are dis- 45 placed 180° relatively to one another, the levers 20 and 21 are alternately held at rest and oscillated, the arrangement being such that the one lever oscillates while the other is held at rest, and reversely. This motion 50 is imparted by the angle levers 28 and 29 and the connecting rods 41 and 42 to the pendulum arms 43 and 44, by which the legs of the patient are moved alternately. While the one pendulum oscillates, in consequence 55 of the form of the cam-grooves 14, 15 the other is held so that it cannot be moved by the patient. If the apparatus is to be operated manually, the clutch 58 is caused to engage with the sprocket wheel 59 and the 60 crank-handle 60 is rotated.

I claim:

1. In apparatus for imparting motion to the legs of patients, the combination, with a frame, of two pendulum arms mounted to

oscillate thereon for attachment to the legs 65 of a patient, and means for alternately oscillating said arms, each of said arms being at rest while the other is being oscillated.

2. In apparatus for imparting motion to the legs of patients, the combination, with a 70 frame, of two pendulum arms mounted to oscillate thereon for attachment to the legs of a patient, a shaft carrying two cams, each comprising an operative circular and elliptical portion and being displaced one hundred 75 and eighty degrees relatively to the other on said shaft, and rods moved by said cams to alternately oscillate said arms and hold at rest each of said arms while the other oscillates. 80

3. In apparatus for imparting motion to the legs of patients, the combination, with a frame, of two pendulum arms in vertical direction adjustably mounted to oscillate thereon for attachment to the legs of a 85 patient, and means for alternately oscillating said arms, each of said arms being at rest while the other is being oscillated.

4. In apparatus for imparting motion to the legs of patients, the combination, with a 90 frame, of a slide movable vertically thereon, means for raising and lowering said slide, two pendulum arms pivotally mounted on said slide for attachment to the legs of a patient, and means for alternately oscillating 95 said arms, each of said arms being at rest while the other is being oscillated.

5. In apparatus for imparting motion to the legs of patients, the combination, with a frame, of two pendulum arms mounted to 100 oscillate thereon for attachment to the legs of a patient, and means for alternately oscillating said arms, each of said arms being at rest while the other is being oscillated, and means for varying the amplitude of oscillation of said arm. 105

6. In apparatus for imparting motion to the legs of patients, the combination, with a frame, of two pendulum arms mounted to oscillate thereon for attachment to the legs 110 of a patient, two connecting-rods pivotally and adjustably connected to said arms, a shaft carrying two cams, and two levers each pivotally connected to one of said connecting-rods and carrying a roller controlled 115 by one of said cams, said cams each comprising an operative circular and elliptical portion and being displaced one hundred and eighty degrees relatively to the other on said shaft. 120

In testimony that I claim the foregoing as my invention, I have signed my name in presence of two subscribing witnesses.

THEODOR BÜDINGEN.
